CLAIM

I claim the ornamental design for a film-transferring device, as shown and described.

DESCRIPTION

The present article dispenses a film-like adhesive applied to a surface.

FIG. 1 is a front elevational view showing my new design for a film-transferring device;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a cross-sectional view thereof taken along line 7—7 indicated in FIG. 1;

FIG. 8 is a reference view thereof showing state of use; and,

FIG. 9 is a perspective view thereof, as viewed from the left.

In the cross-sectional view taken along line 7—7, the portions indicated by the left-side-up hatching are transparent.
